UNITED STATES PATENT OFFICE.

PERCIVAL H. TRUMAN, OF EVANSTON, ILLINOIS, ASSIGNOR TO OTTO R. BARNETT, OF CHICAGO, ILLINOIS.

RAIL-STAY.

1,150,559.

Specification of Letters Patent. Patented Aug. 17, 1915.

Application filed March 10, 1913. Serial No. 753,268.

To all whom it may concern:

Be it known that I, PERCIVAL H. TRUMAN, a citizen of the United States, residing at Evanston, in the county of Cook and State of Illinois, have invented certain new and useful Improvements in Rail-Stays, of which the following is a specification.

My invention relates to rail stays sometimes termed "rail anchors" or "anti-creepers," and the invention has for its principal object to provide a novel device of this sort so constructed that the relatively movable parts forming the clamp on the rail have a positive engagement one with another when in operative position, which prevents the separation of these parts and hence the loosening of the clamp on the rail.

A further object is to provide a rail stay comprising two clamping or rail engaging members one of which is somewhat resilient so that the contraction of the rail due to change in temperature after the device is applied thereto will be taken up and therefore the integrity of the clamp preserved.

The invention has for a further object to provide a device which will be light, strong and inexpensive to manufacture, and which, moreover, can be readily applied to the track in the places required.

In the drawings, the invention is illustrated in two preferred embodiments. It will be obvious that the same principle might be utilized in somewhat different constructions.

With reference to the drawings, Figure 1 shows a side elevation of a device embodying one form of the invention as applied to a rail, the rail being shown in cross section and the tie in elevation. Fig. 2 is a plan view of the parts shown in Fig. 1; Fig. 3, a sectional plan taken on line 3-3 of Fig. 1; Fig. 4, a view, in perspective, of the resilient wedge; Fig. 5, a view, in perspective, of a modified construction shown as applied to the rail; Fig. 6, a plan view illustrating this construction; Fig. 7, a sectional plan thereof corresponding to the sectional plan shown in Fig. 3; and Fig. 8, a view, in perspective, of the resilient member employed in the construction shown in Figs. 5 to 7 inclusive.

Like characters of reference designate like parts in the several figures of the drawings.

In the drawings, A designates a railroad rail and B one of its supporting ties.

Referring first to Figs. 1 to 4, inclusive,

the device shown therein consists of a strap or yoke C, which is preferably, though not necessarily, made of malleable iron and is provided with a tie abutting flange D, and of a hollow, resilient wedge or key E which may conveniently be made of sheet steel 60 pressed into suitable form. The strap C is formed at one end with a jaw F which engages one edge of the rail base and at the other with a preferably larger jaw G. The 65 spring wedge E is driven in between the jaw G and the adjacent edge of the base of the rail. The preferred form of wedge is best shown in Fig. 4. It is pressed or formed so as to provide a lip H, extending 70 under the rail base, and a double or folded lip I which overlaps the upper surface of said rail base. The upper or outer surface of the wedge member and the inner surface of the jaw G are preferably provided 75 with co-engaging shoulders which prevent the wedge from backing out of its operative position. For example, the wedge may be formed to this end with pressed out ribs J and the inner surface of the jaw with teeth 80 K. It will be observed that the wedge, when driven into place, will yield so as to allow the ribs J to pass over the teeth K. The wedge may be driven into the jaw as 85 far as may be necessary. The resiliency of the wedge therefore serves two purposes: First, it allows the wedge to yield to permit its locking shoulders to pass the co-engaging shoulders on the jaw, and, second, it serves to take up any looseness in the 90 clamp resulting, for example, from the contraction of the rail base due to change in temperature after the device is applied.

In Figs. 5 to 8 inclusive is shown another rail stay constructed on the same general 95 principle. The resilient wedge member L, in this construction, is provided with a tie abutting flange M and the strap N is driven upon the wedge, the wedge being the stationary member of the device and the strap 100 the movable member.

I claim:

1. In a rail stay, the combination with a tie abutment for engagement with the side of a tie, of a rail clamp comprising two metallic members which are relatively movable to produce the clamping action and one of which is compressible transversely with respect to the direction of said relative movement. 110

2. In a rail stay, the combination with a tie abutment for engagement with the side of a tie, of a rail clamp comprising two metallic members which are relatively movable to produce the clamping action and one of which is compressible transversely with respect to the direction of said relative movement, said members being provided with co-engaging shoulders, for the purpose described.
3. In a rail stay, the combination with a tie abutment for engagement with the side of a tie, of a rail clamp comprising two metallic members, one of which is movable with respect to the other, in a direction longitudinal of the rail to produce the clamping action, and one of which members is compressible.
4. In a rail stay, the combination with a tie abutment for engagement with the side of a tie, of a rail clamp comprising two metallic members, one of which is movable with respect to the other, in a direction longitudinal of the rail to produce the clamping action, and one of which members is compressible, said members being provided with co-engaging shoulders, for the purpose described.
5. In a rail stay, the combination with a tie abutment for engagement with the side of a tie, of a rail clamp comprising a strap which extends under and around the base of the rail, and a resilient wedge which intervenes between one end of said strap and the rail.
6. In a rail stay, the combination with a tie abutment for engagement with the side of a tie, of a rail clamp comprising a strap which extends under and around the base of the rail, and a resilient wedge which intervenes between one end of said strap and the rail, said wedge being formed with lips engaging the upper and under surfaces of the rail base respectively.
7. In a rail stay, the combination with a tie abutment for engagement with the side of a tie, of a rail clamp comprising a strap which extends under and around the base of the rail, and a resilient wedge which intervenes between one end of said strap and the rail, said strap and wedge being formed with co-engaging shoulders for the purpose described.
8. In a rail stay, the combination with a tie abutment for engagement with the side of a tie, of a rail clamp comprising two metallic members relatively movable to produce the clamping action, one of which consists of a resilient wedge.
9. In a rail stay, the combination with a tie abutment for engagement with the side of a tie, of a rail clamp comprising two metallic members relatively movable to produce the clamping action, one of which consists of a resilient wedge, said members being formed with co-engaging shoulders, for the purpose described.
10. A rail stay comprising two relatively movable members adapted to provide a clamp for the base of the rail, one of said members consisting of a resilient wedge and one of said members being formed with a tie abutment for engagement with the side of a tie, said members being provided with co-engaging shoulders, for the purpose described.
11. In a rail stay, the combination with a tie abutment for engagement with the side of a tie, of a rail clamp comprising a rigid member, and a hollow, transversely compressible key.
12. In a rail stay, the combination with a tie abutment for engagement with the side of a tie, of a rail clamp comprising a rigid member, and a hollow, transversely compressible key, said key and rigid member being formed with coengaging shoulders to prevent the key from being displaced.
13. A rail stay comprising two rail clamping members, one of which is hollow and compressible and one of which is provided with a tie abutment for engagement with the side of a tie.
14. A rail stay comprising two rail clamping members, one of which is hollow and compressible and one of which is provided with a tie abutment for engagement with the side of a tie, said members being formed with coengaging shoulders, for the purpose described.
15. A rail stay comprising an elastic member and a yoke adapted to extend around the base of the rail and said elastic member and put the latter under strain, one of said members being provided with a tie abutment for engagement with the side of a tie.
16. A rail stay comprising an elastic wedge-shaped member and a yoke adapted to extend around the base of the rail and said elastic member and put the latter under strain, one of said members being provided with a tie abutment for engagement with the side of a tie.
17. In a device for preventing the longitudinal creep of a railroad rail, the combination of rail engaging means extending around the base flange of the rail, and a resilient metallic element adapted to be driven between said rail engaging means and the rail and thereby subjected to a bending strain.
18. In a device for preventing the longitudinal creep of a railroad rail, the combination of rail engaging means extending around the base flange of the rail, and a resilient wedge adapted to be driven between said rail engaging means and the rail and thereby subjected to a bending strain.
19. In a device for preventing the longitudinal creep of a railroad rail, the combination of rail engaging means extending around the base flange of the rail, and a resilient metallic element adapted to be driven between said rail engaging means and the rail and thereby subjected to a bending strain.

nation of rail engaging means extending around the base flange of the rail, and a hollow compressible element adapted to be driven between said rail engaging means and the rail and thereby subjected to a bending strain.

20. In a device for preventing the longitudinal creep of a railroad rail, the combination of rail engaging means extending

around the base flange of the rail, and a hollow compressible wedge adapted to be driven between said rail engaging means and the rail and thereby subjected to a bending strain.

PERCIVAL H. TRUMAN.
